UNITED STATES PATENT OFFICE.

RUDOLPH BECKER, OF ROSELLE PARK, NEW JERSEY, ASSIGNOR TO THE SINGER MANUFACTURING COMPANY, A CORPORATION OF NEW JERSEY.

THREAD-CONTROLLING MECHANISM FOR SEWING-MACHINES.

1,386,307.

Specification of Letters Patent.

Patented Aug. 2, 1921.

Original application filed November 5, 1917, Serial No. 200,273. Divided and this application filed November 25, 1918. Serial No. 263,990.

To all whom it may concern:

Be it known that I, RUDOLPH BECKER, a citizen of the United States, residing at Roselle Park, in the county of Union and 5 State of New Jersey, have invented certain new and useful Improvements in Thread-Controlling Mechanism for Sewing-Machines, of which the following is a specification, reference being had therein to the 10 accompanying drawings.

This invention relates to sewing machines and particularly to mechanism for controlling the thread during the formation of 15 stitches, being a division of application Serial No. 200,273, filed November 5, 1917.

The invention is directed particularly to a new and useful mechanism for controlling the thread of a straw braid sewing machine of a type which has met with wide satisfaction 20 and in which a pair of upwardly directed needles, one apertured and the other hooked, penetrate through the work from its lower side and on the upper side of the work coöperate with loopers or other thread 25 handling mechanism to form a chain stitch in which only short lengths of thread appear on the fair side of the goods at relatively widely spaced intervals.

The invention aims to provide a better 30 control of thread in this type of machine than heretofore and enables different lengths of stitches being set properly and without special adjustment of the thread controlling mechanism, thereby decreasing the amount 35 of work the operator has to do and insuring the proper formation of a stitch on any and all machines that may be in the factory regardless of the length of stitch that is best suited to the character of the braid being 40 formed into a hat.

The construction comprises essentially an eye-ended take-up arm arranged to vibrate between a pair of thread-guides and a nipper or thread-clamp which intermittently 45 grips the thread, both the take-up and the nipper being governed and automatically adjusted from a common lever, preferably the feed regulator.

The invention is illustrated in the accompanying drawings, in which Figure 1 is a 50 front side elevation of the machine. Fig. 2 is a transverse section through the lower part of the frame of the machine showing the feed regulator and one side of the take-

up. Fig. 3 is a detail in cross section showing the other side of the take-up. Fig. 4 is a sectional detail of the nipper. Fig. 5 is a plan view of a barrel portion of the nipper. Fig. 6 is a rear side elevation looking at that portion of the frame of the machine on which the nipper and take-up are mounted. Fig. 7 is a diagram of the stitch, the successive stitches in the formation of which are illustrated in Figs. 8 to 11 inclusive and Fig. 12 is a diagram representing the relative motion of the eyes of the needle and take-up on both a long and short stitch.

The invention is illustrated applied to a straw-braid sewing machine having an eye-pointed needle 1 and a hook needle 2 actuated by suitable mechanism such as is 70 fully disclosed in my previously mentioned parent application Serial No. 200,273 which also discloses a suitable form of presser-foot and looper mechanism. The feeding mechanism, as more fully disclosed in said parent case, may include a feed rocker 3 hinged on the shaft 4 and having a slot 5 receiving a slide-block 6 whose position therein is variable to change the length of stitch. 80

The position of the slide-block 6 in the slot of the feed-rocker is governed by a feed regulator in the form of a lever 7, Fig. 2 pivoted on the main-shaft 8 adjacent the feed-eccentric 9 and having a fork 10 curved 85 as shown at the end of its long arm embracing a friction roll 11 carried by the block 6 in the slotted feed-rocker 3 so that the operator is enabled on manipulating the opposite end of the lever to shift the block 90 to and from the fulcrum of the feed-rocker to vary the length of feed or stitch.

Convenient control of the feed regulator is provided by extending a pin 12, Figs. 2 and 3 secured in the short arm 13 of the 95 lever through a slot 14 in the front wall of the frame in register with which slot is a correspondingly shaped opening in a segment plate 15 secured by screws 16 to the frame and provided on opposite sides of the 100 elongated opening with a series of sockets 17. A handle 18, Fig. 3 is sleeved on the end of the pin 12 and a coiled spring 19 is interposed between the bottom of the socket in the handle and the head of a screw 20 105 threaded into the pin. A pair of diametrically disposed pins 21, Fig. 2 are arranged on the inner end of the handle 18 and are

adapted to seat in the sockets 17 in the plate. These sockets and pins may be of such size, shape and spacing as to permit of any desired variations in the length of 5 stitch.

The thread controlling mechanism comprises a take-up and a nipper located on the front wall of the frame convenient to the operative.

10 Two thread guiding eyes 22 are adjustably secured as indicated at 23 or in any suitable manner on the front wall of the machine in line with a slot 24 in the frame so that the apertured free end 25 of the arm 26 of the 15 take-up may vibrate between the eyes. The eyed-arm 26 of the take-up is clamped by a set-screw 27 in one end of a lever 28, Figs. 2, 3 and 6, which is fulcrumed intermediate its ends as shown at 29 to a rock-arm 30 20 which in turn is fulcrumed on the pin 31 fixed horizontally in the central web below and in front of the main-shaft of the machine. The lever 28 and the eye-ended arm 26 together constitute the take-up proper 25 and move as one. For actuating the take-up a pitman 32 connects the lower end of the lever 28 with an eccentric 33 on the main-shaft while a link 34 connects its upper end with a pin 35 secured by a set-screw 36 in a lug 37 integral with the eccentric-strap embracing the feed eccentric 9. When the feed is regulated the action of the 30 take-up is varied simultaneously with that of the nipper by reason of the angular rotation 35 of one end of the link 34 about the center of the feed actuating eccentric.

The nipper, see Figs. 4, 5 and 6, comprises a clamping head or button 38, whose stem 39 is threaded into the end of a pitman 40 strapped about an eccentric 41 on the main-shaft, and an adjustable abutment which embraces the stem. This abutment consists of a cylindrical barrel 42 in whose outer wall is an inclined slot 43 receiving 45 the stud-end 44 of a screw 45 tapped into the frame. An arm 46, Fig. 6 fixed to the rear end of this barrel has a forked extremity 47 embracing the pin 12 in the manipulating end of the feed regulator. When the feed 50 is changed the barrel is turned by means of this arm forked about the feed regulator and the inclination of the slot in the barrel is such that nipping of the thread is timed to occur later when the stitch is long than 55 when it is short and vice versa. So that the thread will not be crushed and in order to allow the meeting faces of the abutment and clamping head to come together squarely, a washer 48, Fig. 4 is loosely 60 mounted in the barrel. A spring 49 of the proper strength resting on the rear end of the barrel, thrusts the washer toward the clamping head or button and against the in-turned restraining flange 50 at the front end 65 of the barrel.

A constant tension device 51 of any suitable form is secured on the front wall of the vertical standard and thread from any suitable source is passed through this tension device, through thread-eyes 52, 53 on opposite 70 sides of the nipper, through the thread-eyes 22, and the eye of the take-up to a tube 54 set at an inclination in a horizontal plane in the frame with its delivery end adjacent the path in which the needles reciprocate. The 75 thread is then passed up along the groove in the needle 1 and through its eye.

The operation of the thread-controlling mechanism will now be described.

When the needles enter and pass up 80 through the work they draw upon the previously formed loop which has been shed by the hook and left encircling the shank of the eye-pointed needle. In the case of a long stitch the previously formed loop is already tight or nearly so and thread is consequently drawn by the eye-pointed needle from the supply, the nipper of course being open to permit such drawing action. In the case of a short stitch the previously formed 85 loop is not snug about the shank of the eye-pointed needle and the latter passes some distance above the work before the previously formed loop is tightened about the shank of the needle, after which the needle 90 in its continued rise above the work draws thread from the supply which is now free because the nipper releases its grip upon the thread about the time or a little after the needle-eye reaches the upper surface of the 95 work.

The eye-pointed needle in its descent from its highest position to a position beneath the work supplies the same amount of thread for the stitch being formed whether it be long or 100 short. In the case of a short stitch the needle supplies too much thread and in the case of a long stitch it does not supply enough thread. Thus the thread-controlling mechanism is called upon to perform a function in making a short stitch that is diametrically opposed to the function it must perform in making a long stitch. This is to say, in the case of a long stitch the thread-controlling mechanism must function mainly 110 as a pull-off to meet a deficiency of thread and in the case of a short stitch mainly as a take-up to handle an excess of thread. Consequently while the needles are moving below the work and during the feeding action, 115 thread is given up (when a long stitch is being made) by the arm 26 as it rises toward the line of the fixed eyes 22 and is taken up (when a short stitch is being made) by the arm 26 as it moves above and away from the line of the eyes 22. This will be clear from an examination of the curves shown in Fig. 12 without further explanation. These curves graphically express the thread-control 120 throughout a stitch-forming cycle, and 125 130

may be distinguished by the abbreviations N. E., T. L. and T. S., which respectively represent the movement of the needle-eye, the take-up on a long stitch and the take-up 5 on a short stitch.

It is to be noted that the needle-eye curve N. E., Fig. 12 was plotted from the machine with the presser-foot removed and consequently the maximum height of the needle- 10 eye above the throat-plate therein shown is less than it would ever be in actual practice with the material under the presser-foot. It is to be noted also that vertical distances in Fig. 12 represent the actual travel of the 15 needle-eye and take-up eye while the dia- grammatic views in Figs. 8—11 inclusive are double the actual size. In Fig. 12 the duration of nip and of feed are also indicated.

It will be seen that the thread-controlling 20 mechanism comprises a variable nipper and a variable take-up. The grip of the nipper varies from almost nothing on a long stitch to about a third of a revolution of the main-shaft on a short stitch. The throw of the 25 take-up on a long stitch is a little less than its throw on a short stitch but its vibrations are largely below a line connecting the adjacent fixed eyelets 22 in the case of a long stitch whereas they are largely above the 30 same in the case of a short stitch. By the simple arrangement for effecting this change in the movement of the take-up arm 26 together with the duration of the nipper's grip upon the thread, the action of the eyed arm 35 26 during a long stitch is substantially that of a pull-off and during the formation of a short stitch is substantially that of a take-up.

By making the variations in the stroke of the needle take place solely at the upper end 40 of the stroke it will be seen that the eye-pointed needle will draw off more thread when the work increases in thickness than in the machines of the prior art in which variations in the needle's stroke occur at 45 both ends of its stroke. Obviously increasing the drawing action of the eye-pointed needle when the work increases in thickness meets the demands of seam-formation better than the organizations in the prior art 50 having the same type of controlled needle operating mechanism.

The wire from which the eyes 22 are bent or formed is preferably light enough to permit of a slight spreading or separation 55 of the eyes when the strain put upon the thread running to the take-up is the greatest, as it is when a short stitch is being made and the take-up is in the position shown in Fig. 1.

60 Due to the adjustability of the eccentric 33 for the take-up, the eccentric 41 for the nipper, and the thread-eyes 22 the proper relative timing and the extent as well as the duration of action of these thread-control- 65 ling elements may be varied to suit the exact

requirements of the stitch for various kinds of work. It is also to be noted that the eccentric (or crank equivalent) actuation of the take-up and of the nipper enables a machine of this type attaining a higher speed 70 than those heretofore in use equipped with a cam driven take-up or nipper.

Having thus set forth the nature of the invention, what I claim herein is:—

1. In a sewing machine having stitch-forming and work-feeding mechanism, in combination, a take-up, a nipper, and means for simultaneously varying the extent of the take-up's throw and the timing of the 75 nipping action.

2. In a sewing machine, stitch-forming and work-feeding mechanism, thread-controlling mechanism including a take-up and a nipper, devices for varying the length of feed, and means governed by said devices 85 for changing the action of both the take-up and the nipper whereby the stitch may be formed properly conformably with its length.

3. In a sewing machine having stitch-forming and work - feeding mechanism, thread-controlling mechanism including a take-up and a nipper, a lever for varying the action of the work-feeding mechanism to change the length of stitch, and means gov- 90 erned by said lever for changing the action 95 of the nipper and the take-up to suit different lengths of stitch.

4. In a sewing machine having a main-shaft and stitch-forming mechanism, work 100 feeding mechanism including a slotted feed-rocker, an eccentric element on said main-shaft, a strap connected to said eccentric element and also adjustably connected to said slotted rocker, a lever for adjusting said 105 strap to vary the angular displacement of said slotted feed-rocker, a pin carried by said strap, a take-up lever fulcrumed on a movable support, a link connected to said pin, a second eccentric element on said main-shaft and a pitman connected thereto, said pitman and link being joined to said take-up lever on opposite sides of its movable 110 fulcrum support.

5. In a sewing machine having a main- 115 shaft and stitch-forming mechanism, work-feeding mechanism, and thread-controlling mechanism including a take-up and a nipper, spaced eccentrics on said main-shaft for separately operating said take-up and said 120 nipper, a feed-regulator, and means governed by said feed-regulator for altering the action of both said take-up and nipper when the feed is changed.

6. In a sewing machine, a main-shaft, 125 stitch - forming mechanism, work - feeding mechanism, and thread-controlling mechanism including a nipper, said nipper having a clamping head actuated from said main-shaft, an adjustable abutment coöperating 130

- with the clamping head, a feed-regulator, and means governed by the feed-regulator for varying the position of the abutment relative to the clamping head.
5. 7. in a chain stitch machine having eye-pointed and hooked needles arranged in tandem and coöperating looper mechanism, adjustable work-feeding mechanism, and thread-controlling mechanism including a 10 nipper, a pair of relatively fixed thread-guides and a thread-carrying arm movable therebetween, and means for variably actuating said thread-carrying arm in coöperation with the nipper to mainly pull off 15 thread for a long stitch and to mainly take up thread for a short stitch.
8. In a chain stitch machine having eye-pointed and hooked needles arranged in tandem and coöperating looper mechanism, 20 adjustable work-feeding mechanism, and thread-controlling mechanism including a variable nipper, a pair of relatively fixed thread-guides and a thread-carrying arm movable therebetween, and means for throwing 25 said thread-carrying arm mainly to one side of the line of said fixed thread-guides on a long stitch and mainly to the opposite side of the line of said fixed thread-guides on a short stitch whereby the thread-controlling mechanism functions mainly as a 30 pull off on a long stitch and mainly as a take-up on a short stitch.
9. In a straw braid machine having eye-pointed and hooked needles, in combination, 35 feeding mechanism, means for adjusting the feeding mechanism, nipping mechanism, take-up mechanism, means for adjusting the nipping and take-up mechanisms, eccentric elements for actuating said nipping and 40 take-up mechanisms, and operative means connecting the feeding mechanism and the adjusting means for the nipping and take-up mechanisms.
10. In a straw braid machine having eye-pointed and hooked needles, in combination, 45 feeding mechanism and adjusting means therefor, nipping mechanism, and a take-up including a lever fulcrumed intermediate its ends, controlling means including a link secured to one end of said lever and to the feeding mechanism, and eccentric operated means for actuating the other end of said lever.
11. In a straw braid machine having eye-pointed and hooked needles, in combination, 55 feeding mechanism, nipping mechanism, and a take-up including a lever fulcrumed intermediate its ends, controlling means including a link secured to one end of said lever and to the feeding mechanism, and eccentric operated means for actuating the other end of said lever.
12. In a straw braid sewing machine having eye-pointed and hooked needles whose lower limit of movement is fixed, in combination feeding mechanism, means for adjusting the feeding mechanism, thread-controlling mechanism including a nipper and take-up, 60 and means connected with the feeding mechanism for automatically adjusting said take-up whereby it will act in coöperation with the nipper mainly as a pull-off for the thread when a long stitch is made and as a take-up for the thread when a short stitch 65 is being made.
13. In a straw braid sewing machine having eye-pointed and hooked needles whose lower limit of movement is fixed, in combination, feeding mechanism and thread-controlling mechanism comprising a nipper, 70 relatively fixed take-up eyes and a thread-carrying arm movable therebetween, means for operating said nipper to grip the thread but once during each stitch-forming cycle 75 and means connected with the feeding mechanism for automatically varying the action of the thread-carrying arm with variations 80 in the length of the stitch.
14. In a sewing machine having stitch-forming mechanism, work-feeding mechanism, a regulator therefor, thread controlling mechanism including a nipper having coöperating thread clamping elements, means for operating one of said elements and means governed by the feed-regulator for adjusting the other of said elements. 90
15. In a sewing machine having stitch-forming mechanism, work-feeding mechanism and a regulator therefor, thread controlling mechanism including a nipper, 95 means for operating the nipper and means controlled by the feed-regulator but acting independently of the nipper operating means for varying the timing of the nipping 100 action.
- In testimony whereof I have signed my name to this specification.

RUDOLPH BECKER.
